INVENTOR

Alfred J. Lundberg
BY Chas. E. Lounard

ATTORNEY

UNITED STATES PATENT OFFICE.

ALFRED J. LUNDBERG, OF SAN FRANCISCO, CALIFORNIA.

FLUSHING TANK.

Application filed February 25, 1920. Serial No. 361,285.

To all whom it may concern:

Be it known that I, ALFRED J. LUNDBERG, a citizen of the United States, residing at the city and county of San Francisco and State 5 of California, have invented a new and useful Improvement in Flushing Tanks, of which the following is a specification.

This invention relates to a flushing tank and especially to a siphon priming attachment therefor.

One of the objects of the present invention is to provide a simple, substantial and easily operated mechanism whereby the filling and discharging of flushing tanks and the like 15 may be actuated, and especially to provide a mechanism whereby the use of submerged valves, etc., which might cause leakage, may be eliminated.

Another object of the invention is to provide 20 a siphon member through which the flushing water is discharged, and in conjunction therewith means for automatically raising the water level in the tank to prime the siphon member when discharging.

Another object of the invention is to provide 25 means to prevent flushing or emptying of the tank until it is full and able to make a complete flush.

Further objects will hereinafter appear.

The invention consists of the parts and the 30 construction, combination and arrangement of parts as hereinafter more fully described and claimed, having reference to the accompanying drawings, in which—

Fig. 1 is a central vertical longitudinal section through the flushing tank showing the mechanism employed.

Fig. 2 is a cross section of the tank.

Referring to the drawings in detail; A indicates 35 a tank of suitable construction, and 2 a discharge pipe connected therewith. This pipe extends upwardly into the tank and terminates in the siphon member 3. The upper bend of the siphon is flattened as at 4, and means are provided for priming the siphon whenever it is desired to empty the tank for flushing purposes. The means employed consists of an auxiliary tank B, an inlet valve 5, a float 6 whereby it is actuated, 45 and a latch 7. The inlet valve is constructed in any suitable manner and is connected with a source of water supply by means of a pipe 8. The valve is normally closed as shown at 9 by means of a float actuated lever 50 10. This lever is pivotally mounted as at

11 on an extension 12 formed on the valve casing, and it is provided with a fork-shaped rocker arm 13 which straddles a stem 14, connected with the valve 9; movement of the rocker arm 13 being transmitted to move the 60 valve 9 and the stem 14 longitudinally by positioning the fork-shaped end of the rocker arm between a pair of collars formed or otherwise secured on the stem. Water admitted when the valve 9 is open, passes 65 through a pipe 16 and empties directly into the auxiliary receiving tank B. This tank is pivotally mounted on brackets 17, and the pivotal connections are eccentrically positioned to permit overbalancing or tilting 70 movement of the auxiliary tank when this is filled. The auxiliary tank is normally held in position by the latch 7, said latch engaging a shoulder or lug 18 formed on the side of the tank, and the tank is also held in up- 75 right position by a secondary latch 19, the function of which will hereinafter be described.

The operation of the mechanism employed will be as follows:

When the main tank A is empty, it is obvious that the float 6 will rest on the bottom of the tank and that the lever 10, to which it is attached, will assume a tilted position. This movement or position of the lever 10 80 and the float 6 opens the valve 9 and thereby permits water to enter through pipe 16 and discharge into the auxiliary tank B. This tank when filled overflows and fills the main tank A and the water will continue 85 rising therein until the float reaches a predetermined position. The gradual rise of the float and lever naturally closes the valve 9 and complete closure of the same is obtained when a desired water level is reached. 90 If it is desired to empty the tank, it is only necessary to lift upwardly on a lever 7^a which forms an extension of the latch 7. This lever and latch are pivotally mounted as at 20 on a bracket member 21, and movement of 95 the lever 7^a in an upward direction will therefore pull the latch out of engagement with the lug 18 and thereby permit the auxiliary tank to tilt about its pivotal connection 100 17 and assume the dotted line position shown 105 in Fig. 2. The water contained therein is therefore added to the supply of the main tank and the water level is thereby raised, the quantity added being sufficient to permit an overflow through the siphon 3. This 110

overflow causes priming of the siphon and the entire contents of the main tank A will therefore be discharged. The float 6 will therefore drop and the inlet valve 9 will again open and refill the tank.

By referring to Figs. 1 and 2, it will be seen that a second latch 19 has been provided. This latch is also pivotally mounted as at 22 on a bracket 21, and it is provided with a lever extension 23. The main float lever 10 is also provided with an extension as shown at 24. The upper end of this extension is hook-shaped as at 25 and engages the outer end of the lever 23. When the float 15 reaches its lowermost position, that is, when the tank is empty the opposite end of the lever or the extension 24 will reach a raised position indicated by dotted lines as at 26. This permits the latch 19 to swing 20 into engagement with the lug 18 and thereby locks the auxiliary tank against tilting movement about the pivotal connection 17, that is a counterweight 27 is placed on the tank and this counterweight returns the 25 tank to normal horizontal position the moment it has been emptied. The float simultaneously drops to the bottom of the tank and the opposite end of the float lever is therefore raised, thereby permitting the 30 latch 19 to swing inwardly and engage the lug 18. The auxiliary tank is therefore automatically locked against tilting movement while it, together with the main tank, is being refilled and it is therefore impossible to 35 prime the siphon or empty the tank until it has been completely refilled, that is the float 6 must reach its uppermost position before the projection 24 on the float lever becomes sufficiently depressed to swing the latch 19 40 out of engagement.

When latch 19 has been swung out of engagement by the rise of the float, it is obvious that latch 7 will support the tank and that if this is swung out of engagement by 45 raising the lever 7^a, tilting movement of the tank will be permitted. It is therefore impossible to flush or empty the tank except after it has been completely refilled. This is of great importance as it reduces waste of 50 water to a minimum.

By referring to Figs. 1 and 2, it can be seen that the only valve employed is that indicated at 9; that all connections with the bottom of the tank are stationary and permanent, and that leakage is entirely avoided. A discharge valve is not required due to the siphon 3 employed and cost of construction is therefore materially reduced. While a more or less specific form of inlet valve 55 is employed, I wish it understood that any other form may be employed as this feature does not form an important part of the invention. I further wish it understood that various changes in the construction, combination and arrangement of parts may be 60

made by those skilled in the art without departing from the spirit of the invention so claimed.

Having thus described my invention, what I claim and desire to secure by Letters Patent is—

1. In a device of the character described, a tank, an inlet valve, a siphon actuated discharge pipe, means for priming the siphon for discharging, and means for preventing 75 priming of the siphon and discharging of the tank when refilling the tank.

2. In a device of the character described a tank, a float actuated inlet valve, a siphon actuated discharge pipe, means for priming 80 the siphon for discharging, and means actuated by the float for preventing priming of the siphon and discharging of the tank while the inlet valve is open and refilling.

3. In a device of the character described 85 a tank, a siphon actuated discharge pipe connected with the tank, means in the tank for raising the normal water level to prime the siphon for discharging, automatic actuated refilling means, and means actuated thereby 90 for preventing priming of the siphon during the refilling operation.

4. A flushing device comprising a main tank, a siphon discharge pipe connected therewith, an auxiliary tiltable tank mounted within the main tank, means for maintaining a predetermined water level in said tanks, a latch mechanism cooperating with said means to retain said auxiliary tank from tilting during the filling of said tanks, 95 and a second latch mechanism independent of the first named latch, adapted to retain the auxiliary tank from tilting after the desired water level is reached and being operable whereby the auxiliary tank may be 100 permitted to tilt to empty the water contained therein into the main tank to raise the water level therein so as to prime the siphon and discharge the water in the main tank therethrough.

5. In a device of the character described a tank, a siphon actuated discharge pipe connected therewith, an auxiliary tank mounted within the main tank, means for maintaining a normal water level in the main tank 115 and in the auxiliary tank, means for holding the auxiliary tank against tilting, said means permitting tilting of the auxiliary tank to empty its contents into the main tank and thereby raise the water level to such 120 an extent that overflow and priming of the siphon is started, means for automatically returning the auxiliary tank to normal position, automatic actuated means for refilling the auxiliary tank and the main tank, and means for locking the auxiliary tank against tilting movement while the main tank is being refilled.

6. In a device of the character described a main tank, an auxiliary tank pivotally 125

mounted therein, said pivots being eccentrically positioned to permit tilting of the tank, a siphon actuated discharge pipe connected with the main tank, an inlet valve 5 adapted to discharge water into the auxiliary tank and by overflow fill the main tank, a float actuated valve adapted to close the supply through the inlet valve when a predetermined level is reached in the main 10 tank, means for holding the auxiliary tank against tilting and for releasing the same, means for automatically returning the auxiliary tank to normal position after it has been filled, and means actuated by the float 15 member for locking the auxiliary tank against tilting movement while the auxiliary tank and the main tank are being refilled.

7. In a device of the character described a main tank, an auxiliary tank pivotally mounted therein, said pivots being eccentrically positioned to permit tilting of the tank, a siphon actuated discharge pipe connected with the main tank, an inlet valve 20 adapted to discharge water into the auxil-

iary tank and by overflow fill the main tank, 25 a float actuated valve adapted to close the supply through the inlet valve when a predetermined level is reached in the main tank, means for holding the auxiliary tank against tilting and for releasing the same, means for 30 automatically returning the auxiliary tank to normal position after it has been tilted, a latch pivotally mounted within the tank, a lug on the auxiliary tank with which said latch is adapted to engage, and a lever on 35 the latch adapted to be engaged by an extension on the float actuated lever, said extension on the float actuated lever adapted to hold the latch in position to prevent tilting of the auxiliary tank while said auxiliary 40 tank and main tank are being refilled.

In testimony whereof I have hereunto set my hand in the presence of two subscribing witnesses.

ALFRED J. LUNDBERG.
